TICUT, A CORPORATION OF CONNECTICUT.

LAMP-LOCK.

1,217,829.

Specification of Letters Patent. Patented Feb. 27, 1917.

Application filed February 24, 1913. Serial No. 750,136.

To all whom it may concern:

Be it known that I, JOSEPH SACHS, citizen of the United States, residing at Hartford, in the county of Hartford and State 5 of Connecticut, have invented certain new and useful Improvements in Lamp-Locks, of which the following is a specification.

This invention relates to lamp-locks or that class of devices which are provided to 10 prevent the surreptitious withdrawal of an incandescent-lamp from its socket, among the principal objects of the invention being the provision of an article of this character which is simple in construction, capable 15 of easy and inexpensive manufacture and which when in operative relation will effectually prevent the lamp from being taken from the socket, unless the lock be destroyed, for instance by the use of a cutting 20 tool or some like implement. It is a well known fact that thieves abstract incandescent lamps from their sockets especially when the same are expensive such as those known as "tungsten" lamps. I provide 25 a lock in the form of a band which preferably encircles both the lamp and its socket and which is preferably in one piece being ordinarily but not necessarily, endless or continuous and adapted in some suitable 30 manner to interlock with at least either the lamp or socket but preferably with both, and which is applied after the lamp has been inserted in said socket so that before the lamp can be taken from place, it will 35 be necessary to cut through said band, which is an operation usually requiring some time and the aid of a tool which thieves do not generally carry. In addition to this the possibility of a thief being detected in the 40 act of cutting through one of the bands, an operation which, as already observed requires some time, will ordinarily deter him from committing the theft.

In the drawings accompanying and forming 45 part of the present specification I have shown in detail several of the many advantageous forms of embodiment of the invention which to enable those skilled in the art to practice the same, will be fully set forth 50 in the following description. I do not restrict myself to this showing; I may depart therefrom in many respects within the scope of my claims following said description.

Referring to said drawings:

Figure 1 is a view of portion of a lamp 55 and its socket in assembled relation, a portion of the socket and a part of a catch member on the lamp being broken away, the view also showing the locking band in vertical section.

Fig. 2 is a view of similar parts, the socket, lamp and catch member being in elevation and the locking band in section, said locking band being of a form different from that shown in said Fig. 1.

Fig. 3 is a view in elevation partly broken away, of a different form of locking band uncontracted.

Fig. 4 is a view corresponding with Fig. 2 but showing the locking band of Fig. 3 70 applied and set or contracted in working relation.

Fig. 5 shows the locking band of Figs. 3 and 4 in operative position, the lamp and socket also partly appearing.

Figs. 6 and 7 are respectively a top plan view and vertical section of another form of locking band showing the same in uncontracted condition.

Fig. 8 is a top plan view of the band 80 shown in the two preceding views in contracted relation.

Fig. 9 is a top plan view of another form of band in uncontracted relation.

Fig. 10 is a view corresponding with Fig. 85 4 of another form of lock.

Like characters refer to like parts throughout the several figures.

My invention as to one of its broader aspects, comprises a one-piece or unitary locking band, preferably but not essentially of endless form. Such an article can be easily and inexpensively made, can be readily applied and when in active relation will positively prevent the withdrawal of a lamp 95 from its socket, it being essential before the lamp can be taken from place that said band be snipped through. Such a band can vary radically as to character and as already stated I have illustrated several of the many 100 forms which said band, can take; there are others within the spirit of my invention. Said band may be interlocked both with the lamp and socket and there may be cases where the band will prevent withdrawal of 105 the lamp from the socket merely by the in-

terlocking grip of the band with one or both of the parts. I can secure said interlocked relation in various ways, for instance and as will hereinafter appear, by distorting or bending portions of the band or ring into engagement with catch portions on either the lamp or socket or both.

Referring first to Fig. 1 which illustrates partly a lamp 2 and its socket 3 both of standard construction, the annular bead 4 on said socket answers suitably as a catch portion for engagement by a part on the locking band 5 which is usually made from some suitable metal as brass. The catch member on the lamp 2 may vary, although the ring 6 meets the necessities, and is preferably but not essentially of some insulating material, as fiber, to insulate the lamp-base from the locking-band 5, said catch-ring 6 surrounding the neck of the lamp and its inner edge being beveled or acute to engage over the upper edge of the metal shell of said base.

Initially the inner diameter of the locking band 5 is greater than the diameters of the bead 4 and catch ring 6; in fact at this time said ring is practically a true cylinder so that said locking band can be freely passed over the socket 3 and so that the lamp can be inserted in the socket while the band is thereon. The said locking-band will then be positioned to bring its lower edge below the bead 4 and its upper edge above the catch ring 6 in which position said locking-band 5 is in readiness to be set which is accomplished by distorting the same, for instance by curling, spinning, crimping or bending the lower portion of said ring over said bead as at 7 and by distorting said band near its upper edge inwardly in such manner as to produce within the same, an annular bead 8 which engages over the upper side of the catch ring 6 so that when the parts are in this relation the lamp cannot be unscrewed from its socket.

Referring now to Fig. 2, the lamp therein shown is denoted by 9, its socket by 10, the split or divided catch ring by 11 and the catch bead by 12, these parts being the same as those already described. The locking band is denoted by 13 and is originally like and is applied similarly to the band 5. After being positioned, the band 13 has punched therefrom the interior spurs or projections 14 which engage against the catch portions 11 and 12 of the lamp and its socket respectively.

Referring now to Figs. 3, 4, and 5, the lamp, socket, lamp catch portion and socket catch portion are denoted by 15, 16, 17 and 18 respectively, the locking-band being denoted by 19 and being initially cylindrical as shown best in Fig. 4 but being distortible into interlocked relation with the catch-portions of the lamp and socket respectively.

The said locking band 19 is provided with interior catch portions such as the annular flanges 20 and 21 coöperating respectively with the catch portions 17 and 18. In this particular form of the device the band as a whole is compressed about the lamp and socket to thus bring the flanges 20 and 21 into interlocked relation with the coöperating catch portions and to facilitate the distortion of said band 19 the opposite edges of the same may be notched as at 22 and the body thereof also have a vertically elongated slot 23. This band 19 is practically applied like the other bands already described and when the two flanges 20 and 21 are in correct positions said band will be compressed or constricted, thus distorting or flexing the same as to move and set the flanges 20 and 21 along or opposite the outer surfaces of the two catch portions 17 and 18, said band being shown in Fig. 5 in its compressed condition. The ring 17 is of metal and is also preferably split, the band 19 having an interior lining 19' of insulating material to thus insulate said band from the base of the lamp.

Referring now to Figs. 6 to 8 inclusive the locking band therein represented is denoted by 24 and it is approximately originally cylindrical. I say "approximately" as said band 24 is not an exact cylinder in the strict sense of the term as it has peripherally several integral channel-like extensions or bowed lugs 25. Said band 24 has inner flanges 26 and 27 duplicates in function of the flanges 20 and 21. The flanges 26 and 27 are, however, not continuous or unbroken, being cut through or interrupted at the bowed lugs 25. This band 24 is applied like the other bands, and when in position to have its flanges 26 and 27 properly placed with respect to the catch portions of the lamp and socket, respectively, will be constricted or contracted about said parts, which action collapses the hollow lugs or ears 25 and also brings the ends of the segments or sections of the flanges 26 and 27 into abutment or practically so as shown in Fig. 8.

In Fig. 9 the locking band 28 is like the band 24 except that instead of having a plurality of the collapsible lugs or ears, it has only one, denoted by 29.

In Fig. 10 the locking band 30 engages with only one of the parts, (the socket 31 as shown) to interlock the same, the lower portion of the shell of said socket being expandable and contractible for example by forming several slits 32 therein. The upper end of said shell of said socket is interiorly flanged as at 33 to engage the catch ring 34 on the lamp 35, the upper portion of said shell thereby presenting a latching part. This latching part is maintained in operative relation by the locking-band 30 which

has one or more tongues 36, adapted to be projected by distortion, or otherwise, through slots or openings 37 in the shell of said socket after said band 30 has been applied.

What I claim is:

1. A lock for holding an incandescent lamp in its socket, provided with separate means for engaging the socket and the lamp, 10 said lock also comprising distortible means for maintaining the lock in operative relation, whereby said two engaging means can jointly act to prevent the lamp being pulled from place when the lock is in operative relation.
2. A lock for holding an incandescent lamp in its socket comprising a locking band having a distortible lamp locking portion, and a split ring in the band for insulating 20 the same from a lamp, the band and ring being disconnected to permit the ring to be applied to the lamp independently of the band, the ring when in place encircling the neck of the lamp below the base shell thereof.
- 25 3. A lock for holding an incandescent lamp in its socket comprising a locking band

having a distortible lamp locking portion, and a split insulating ring held within the band, the two being disconnected to permit the ring to be applied to the lamp independently of the band, the ring when in operative position encircling the neck of a lamp and engaging under the base shell thereof.

4. A lock for holding an incandescent lamp in its socket comprising a locking band 35 having an inwardly distortible portion and also having means to engage the external bead of the socket, and a split insulating ring supported by said distortible portion in the band, the band and ring being disconnected to permit the ring to be applied to the lamp independently of the band, the ring when in position encircling the neck of the lamp and engaging under the base shell thereof.

In testimony whereof I affix my signature in presence of two witnesses.

JOSEPH SACHS.
